COMBINATION PORTABLE COLLAPSIBLE HOIST AND LADDER

George Petkus, Chicago, Ill., assignor to Josephine
Petkus, Chicago, Ill.

Filed Aug. 30, 1968, Ser. No. 13,331

Term of patent 14 years

Int. Cl. D12—02

U.S. Cl. D54—1

FIG. 1 is a front perspective view of my combination portable collapsible hoist and ladder, embodying my new design;

FIG. 2 is a rear elevational view in open position; and
FIG. 3 is a side view in collapsed position of the same.
I claim:

The ornamental design for a combination portable collapsible hoist and ladder, substantially as shown.
